UNITED STATES PATENT OFFICE.

GEORGE W. SWIFT, JR., OF BORDENTOWN, NEW JERSEY.

ENVELOP.

1,151,305.

Specification of Letters Patent. Patented Aug. 24, 1915.

Application filed May 6, 1915. Serial No. 26,210.

To all whom it may concern:

Be it known that I, GEORGE W. SWIFT, Jr., a citizen of the United States, residing at Bordentown, in the State of New Jersey, have invented a certain new and useful Improvement in Envelops, whereof the following is a specification, reference being had to the accompanying drawing.

My invention relates to an envelop for second and lower class mail matter, which must be opened for postal inspection, and having the appearance of a sealed envelop and of the form including a flap which is normally inwardly turned at the open end of the envelop to retain the contents of the latter, but may be turned out to facilitate the inspection aforesaid.

My invention includes the various novel features of construction and arrangement hereinafter more definitely specified.

In the drawing:—Figure I is an elevation of a plane blank from which an envelop embodying my invention may be formed. Fig. II is an elevation of said blank as preliminarily creased, folded and provided with adhesive. Fig. III is an elevation of the envelop formed from the blanks shown in Figs. I and II with the flap at the upper longitudinal edge thereof open to permit the insertion of mail matter, and with the left hand end open for inspection of such matter. Fig. IV is an elevation of said envelop with the flap closed at the upper edge thereof and the left hand end flap turned out for inspection of the contents.

Referring to Fig. I; the plane blank 1, which may be formed of paper or any other suitable fabric, has its lower left hand corner 2 perforated with the line 3 where it may be subsequently severed.

Referring to Fig. II; said blank 1 is creased at the lines 5, 6, 7 and 8, folded at the line 8, to form the inwardly turned inspection flap 10, and provided with the adhesive 11 at its corner 2 within said perforated line 3, and said blank 1 also has its upper longitudinal sealing flap 13 provided with the adhesive 15, and its transverse end sealing flap 16 provided with the adhesive 17.

Referring to Fig. III; said blank 1, provided with adhesive, as above described, is then folded on the line 7 so that its rear wall 19 is attached to its front wall 20 by the adhesive 11 on said flap 10. Said blank is then folded on the line 6 so that the flap

16 overlaps said rear wall 19, upon the back thereof, and is permanently sealed thereto. Of course, when the envelop is thus completed, it is closed at the right hand end and open at the left hand end, from the bottom up to the edge of the adhesive 11 on said flap 10, and, consequently, when the envelop is sealed by folding the flap 13 on the line 5 and causing said flap to adhere to the rear wall 19 by the adhesive 15, its interior may be inspected through its open left hand end, without turning out said inspection flap 10, and, said flap secures the contents of the envelop against accidental escape from said open end. However, if it is desired to thoroughly inspect the contents of the envelop by withdrawing the same through said open end, said flap 10 may be turned outwardly as indicated in Fig. IV; the act of turning it out severing said flap along the line 3 as indicated, and leaving the corner 2 adhering to the front wall 20 of the envelop. It may be observed that said flap is rendered readily accessible to the finger of the operator, and its outward turning movement aforesaid facilitated, by having the upper end of the flap cut off at an angle oblique to the end of the envelop and intermediate of the extent of the opening thereat. After such inspection, said flap 10 may be returned inwardly, from the position shown in Fig. IV to the position shown in Fig. III, but, of course, without reconnecting the corner 2 with said flap. However, as said flap 10 extends across the line 7 at the bottom fold of the envelop, unbroken and imperforate, it is securely held against accidental outward displacement when it is inwardly folded, both initially and when returned after inspection. It may be observed that the purpose and effect of said adhesive corner 2 is to not only hold the front and rear walls of the envelop together at the normally open left hand end of the envelop shown in Figs. III and IV, until they are secured together by the adhesive flap 13, but to normally restrict the opening in said end to less than the distance from the top to the bottom edge of the envelop, and thus prevent withdrawal of any contents of the envelop of that extent, until said corner is severed.

It is not essential that my invention be embodied in envelops of the particular form which I have chosen for illustration. Therefor, I do not desire to limit myself

to the precise details of construction and arrangement herein set forth, as it is obvious that various modifications may be made therein without departing from the essential features of my invention as defined in the appended claims.

I claim:-

1. An envelop having a normally open end, and including front and rear walls and an inwardly folded end flap formed of a single piece of paper; said end flap extending across the bottom fold between said front and rear walls but terminating short of the upper edge of the rear wall and having at said upper edge a portion of said flap adhering to said front wall; restricting the opening in said envelop to an extent which is less than the distance from the top to the bottom of the envelop; said adhering portion being divided from the other portion of said flap by a line of perforations; whereby, said adhering portion may be severed from said flap by outwardly turning the latter, and then afford an end opening of the full extent from the bottom to the top edge of said envelop.

2. An envelop having a normally open end, and including front and rear walls and an inwardly folded end flap formed of a single piece of paper; said end flap extending across the bottom fold between said front and rear walls and having at its upper edge a portion of said flap adhering to said front wall; restricting the opening in said envelop to an extent which is less than the distance from the top to the bottom of the envelop; said adhering portion being divided from the other portion of said flap by a line of perforations; whereby, said adhering portion may be severed from said flap by outwardly turning the latter, and then afford an end opening of the full extent from the bottom to the top edge of said envelop.

3. An envelop having a normally open end, and including front and rear walls and an inwardly folded end flap formed of a single piece of paper; said end flap terminating short of the upper edge of the rear wall and having at said upper edge a portion of said flap adhering to said front wall; restricting the opening in said envelop to an extent which is less than the distance from the top to the bottom of the envelop; said adhering portion being divided from the other portion of said flap by a line of perforations; whereby, said adhering portion may be severed from said flap by outwardly turning the latter, and then afford an end opening of the full extent from the bottom to the top edge of said envelop.

4. An envelop having a normally open end, and including front and rear walls and an inwardly folded end flap formed of a single piece of paper; said end flap having at its upper edge a portion adhering to said front

wall; restricting the opening in said envelop to an extent which is less than the distance from the top to the bottom of the envelop; said adhering portion being divided from the other portion of said flap by a line of perforations; whereby, said adhering portion may be severed from said flap by outwardly turning the latter, and then afford an end opening of the full extent from the bottom to the top edge of said envelop.

5. An envelop having a normally open end, and including front and rear walls and an inwardly folded end flap formed of a single piece of paper; said end flap having a portion adhering to said front wall; said adhering portion being divided from the other portion of said flap by a line of perforations; whereby, said adhering portion may be severed from said flap by outwardly turning the latter.

6. An envelop having a normally open end, and including front and rear walls and an inwardly folded end flap formed of a single piece of paper; said end flap having a portion adhering to said front wall.

7. An envelop having a normally open end, and including front and rear walls and an inwardly folded end flap formed of a single piece of paper; said end flap extending across the bottom fold between said front and rear walls but terminating short of the upper edge of one of said walls and having at said upper edge a portion of said flap adhering to said one wall; restricting the opening in said envelop to an extent which is less than the distance from the top to the bottom of the envelop; said adhering portion being divided from the other portion of said flap by a line of perforations; whereby, said adhering portion may be severed from said flap by outwardly turning the latter, and then afford an end opening of the full extent from the bottom to the top edge of said envelop.

8. An envelop having a normally open end, and including an inwardly folded end flap having an adhering portion connecting the opposed walls of the envelop; whereby said flap is normally held in inwardly turned position by its adhering portion, and said portion restricts the opening in said envelop to an extent which is less than the distance from the top to the bottom of the envelop; said adhering portion being divided from the other portion of said flap by a line of perforations.

9. An envelop having a normally open end, and including an inwardly folded end flap having an adhering portion connecting the opposed walls of the envelop; whereby said flap is normally held in inwardly turned position by its adhering portion, and said portion restricts the opening in said envelop to an extent which is less than the distance from the top to the bottom of the envelop;

whereby, said adhering portion may be severed from said flap by outwardly turning the latter, and then afford an end opening of the full extent from the bottom to the top edge of said envelop.

10. An envelop having an end opening, and including an inwardly folded flap having an imperforate portion extending across the bottom fold of the envelop and terminating at an angle oblique to the end of the envelop, intermediate of said opening, and having a portion at its other end adhering to the inner face of the front wall of said envelop; said adhering portion normally restricting said opening and being divided from the remainder of said flap by a line of perforations; whereby, one end of said flap is accessible to initiate the outward turning movement thereof, and the adhering portion of said flap may be severed from the remainder thereof, by outwardly turning said flap, to thus extend said opening the full width of the envelop.

11. An envelop having an end opening, and including an inwardly folded flap having an imperforate portion extending across the bottom fold of the envelop and terminating at an angle oblique to the end of the envelop, intermediate of said opening, and having a portion at its other end adhering to the inner face of said envelop; said adhering portion normally restricting said opening and being divided from the remainder of said flap by a line of perforations; whereby, one end of said flap is accessible to initiate the outward turning movement thereof, and the adhering portion of said flap may be severed from the remainder thereof, by outwardly turning said flap, to thus extend said opening the full width of the envelop.

12. An envelop having an end opening, and including an inwardly folded flap having an imperforate portion extending across the bottom fold of the envelop and terminating at an angle oblique to the end of the envelop, intermediate of said opening, and having a portion adhering to the inner face of said envelop; said adhering portion normally restricting said opening and being divided from the remainder of said flap by a line of perforations; whereby, one end of said flap is accessible to initiate the outward turning movement thereof, and the adhering portion of said flap may be severed from the remainder thereof, by outwardly turning said flap, to thus extend said opening the full width of the envelop.

13. An envelop having an end opening,
69 and including an inwardly folded flap hav-
ing an imperforate portion extending across
the bottom fold of the envelop and terminat-
ing intermediate of said opening, and hav-
ing a portion adhering to the inner face of
65 said envelop; said adhering portion nor-

mally restricting said opening and being divided from the remainder of said flap by a line of perforations; whereby, one end of said flap is accessible to initiate the outward turning movement thereof, and the adhering 70 portion of said flap may be severed from the remainder thereof, by outwardly turning said flap, to thus extend said opening the full width of the envelop.

14. An envelop having an end opening, 75
and including an inwardly folded flap hav-
ing an imperforate portion extending across
the bottom fold of the envelop and terminat-
ing at an angle oblique to the end of the en-
velop, intermediate of said opening; where-
by, one end of said flap is accessible to initi-
ate the outward turning movement thereof. 80

15. An envelop having an end opening, and including an inwardly folded flap having an imperforate portion extending across the bottom fold of the envelop and terminating intermediate of said opening; whereby, one end of said flap is accessible to initiate the outward turning movement thereof. 85

16. An envelop having an end opening, 90
and including an inwardly folded flap ter-
minating at an angle oblique to the end of
the envelop, intermediate of said opening,
and having a portion adhering to the inner
face of the front wall of said envelop; said 95
adhering portion normally restricting said
opening and being divided from the remain-
der of said flap by a line of perforations;
whereby, one end of said flap is accessible to
initiate the outward turning movement 100
thereof, and the adhering portion of said
flap may be severed from the remainder
thereof, by outwardly turning said flap, to
thus extend said opening the full width of
the envelop. 105

17. An envelop having an end opening, and including an inwardly folded flap terminating intermediate of said opening, and having a portion adhering to the inner face of said envelop; said adhering portion normally restricting said opening and being divided from the remainder of said flap by a line of perforations; whereby, one end of said flap is accessible to initiate the outward turning movement thereof, and the adhering portion of said flap may be severed from the remainder thereof, by outwardly turning said flap, to thus extend said opening the full width of the envelop. 110 115

18. An envelop having an end opening, 120
and including an inwardly folded flap ter-
minating at an angle oblique to the end of
the envelop, intermediate of said opening,
and having a portion adhering to the inner
face of said envelop; said adhering portion 125
normally restricting said opening; whereby,
one end of said flap is accessible to initiate
the outward turning movement thereof, and
the adhering portion of said flap may be
severed from the remainder thereof, by out- 130

- wardly turning said flap, to thus extend said opening the full width of the envelop.
19. An envelop having an end opening, and including an inwardly folded flap terminating intermediate of said opening, and having a portion adhering to the inner face of said envelop; said adhering portion normally restricting said opening; whereby one end of said flap is accessible to initiate the outward turning movement thereof, and the adhering portion of said flap may be severed from the remainder thereof, by outwardly turning said flap, to thus extend said opening the full width of the envelop.
20. An envelop having an end opening, and including an inwardly folded flap having a portion adhering to the inner face of the front wall of said envelop, said adhering portion normally restricting said opening to less than the full width of the envelop and being divided from the remainder of said flap by a line of perforations; whereby, the adhering portion of said flap may be severed from the remainder thereof, by outwardly turning said flap, to thus extend said opening the full width of the envelop.
21. An envelop having an end opening, and including an inwardly folded flap having a portion adhering to the inner face of said envelop, said adhering portion normally restricting said opening to less than the full width of the envelop and being divided from the remainder of said flap by a line of perforations; whereby, the adhering portion of said flap may be severed from the remainder thereof, by outwardly turning said flap, to thus extend said opening the full width of the envelop.
22. An envelop having an end opening, and including an inwardly folded flap having a portion adhering to the inner face of said envelop, said adhering portion normally restricting said opening; whereby, it is necessary to sever the adhering portion of said flap from the remainder thereof, to extend said opening the full width of the envelop.
23. An envelop having an end opening, and including an inwardly folded flap terminating intermediate of said opening, and having a portion adhering to the inner face of said envelop; whereby, one end of said flap is accessible to initiate the outward turning movement thereof, and the adhering portion of said flap must be severed from the remainder thereof, to outwardly turn said flap.
24. An envelop having an end opening and including an inwardly folded flap having an imperforate portion extending across the bottom fold of the envelop and terminating at an angle oblique to the end of the envelop, intermediate of said opening, and having a portion at its other end adhering to the inner face of the front wall of said envelop; said adhering portion normally restricting said opening and being divided from the remainder of said flap by a line of perforations.

In testimony whereof, I have hereunto signed my name at Bordentown, New Jersey, this fifteenth day of April, 1915.
